UNITED STATES PATENT OFFICE.

LOUIS A. CHAPMAN, OF NEW YORK, N. Y., ASSIGNOR TO LONG'S FIXTURES CORPORATION, OF NEW YORK, N. Y., A CORPORATION OF NEW JERSEY.

DISPLAY DEVICE FOR NECKTIES.

Application filed April 14, 1928. Serial No. 269,964.

My invention relates to an improvement in display device for ties and similar merchandise. The object of the invention is a simple contrivance for displaying a necktie or similar article in a pleasing manner, serving also as a tie form.

In the drawings Fig. 1 is a perspective view of my improved display device having a four-in-hand tie held thereon, Fig. 2 is a cross-section through the tie-holding member proper passing through the center thereof from a line bisecting the tie opening, and Fig. 3 is a bottom view of the tie-holding member.

In the drawings *a* designates the tie-holding member and *b* a support therefor; *c* is a four-in-hand necktie shown in knotted condition; *d* is a block of material, preferably circular, provided with a tapped opening *e* 20 to receive a corresponding screw-threaded end (not shown) of support *b*; *f* is a depending apron, spaced from block *d* by a channel *g*, and preferably made integral with such block, for instance, by shaping both from a single piece of stock. The apron *f* as shown in Figs. 1 and 3 almost completely surrounds the block *d* but is cut away in front at *h* to define an opening having the form of an inverted V and simulating the opening of an ordinary turned-down collar. The apron *f* together with so much of block *d* as is visible through V-shaped opening *h*, thus resembles a turned-down collar. A depression *i* may be provided in the upper portion of block *d* to serve for the more convenient display of other goods such as collar buttons, ties or handkerchiefs displayed in any suitable manner.

The space *g* between block *d* and apron *f* 40 is sufficient in width to accommodate the thickness of the tie, and the exterior dimensions of the apron *f* are approximately those of a collar. The portion of the block *d* adjacent to the passage *g* is preferably constructed (as shown in Fig. 2) in the form of a truncated cone to prevent the tie from slipping downward after having been tied in position.

The tie, which may be of any suitable construction, for instance, four-in-hand or bow, is laid around block *d* and then slipped upwardly into space *g* for such a distance as to cause the tie when displayed to have the proper relationship to opening *h*, such relationship being obviously dictated by the

fashion of the moment. Such portion of the tie as extends through opening *h* is then knotted and pulled tight enough to secure the tie against slipping downwardly on block *d*, so that the internal diameter of the neck surrounding portion of the tie is smaller than the external diameter of the lower portion of block *d*.

The tie-holding member *a* is made preferably of wood but may be made of any other suitable rigid material, such as opaque glass or metal; it may, for instance, be made of sheet metal, in which case, of course, the block *d* and apron *f* may be made with a hollow interior.

In order to give my device a novel and pleasing appearance and great strength, I prefer to make the apron of a thickness very much greater than that of the outer apron of a turned-down collar. As illustrated in the drawing, the thickness of the lower portion of the apron is almost three-sixteenths of an inch and of the upper portion, adjacent the top of space *g*, almost a quarter of an inch. For convenience in applying the tie I prefer to make the space *g* much larger than that between the neckband and apron of a turned-down collar. If therefore the exterior of the apron is of the same proportion as that of an average turned-down collar of size 15½, the exterior diameter of any portion of block *d* will be very much smaller than that of the human neck for which such average collar is designed. In order to allow for this difference in size and thus to give the displayed portion of a four-in-hand tie the proper length, I may make provision for taking up more of the concealed portion of the tie by cutting a groove *k*, preferably V-shaped, into some portion of block *d*, preferably the portion immediately opposite the portion *h*. When placing the tie into the tie holder, I form a portion of the former into a loop and lay this into the groove *k*, thus causing a greater length of the tie to be concealed within the device than if this groove were not provided. I may, if desired, unite the portions of the tie lying within the groove by a pin or other fastening means, but I

prefer to lay the loop around a guide pin such as *l*, inserted into block *d*, and may then adjust the tie to the proper position in the usual manner as it will readily slide on such pin, especially if the portions of

the block *d* where the groove *k* meets the space *g* are rounded off as shown in Fig. 3. In order to permit an adjustment of the length of the tie portion concealed within 5 the device, I provide additional apertures *m*, screw-threaded or otherwise adapted to receive the guide pin *l*. The provision of this groove permits the display of bow ties of varying lengths on my device.

- 10 My display device serves also as a tie-form, as the tie is knotted after it has been placed in the space *g*. This makes it unnecessary to employ a separate tie form for knotting the tie before placing it on display.
- 15 It will, of course, be understood that the tie-holding device *a* may be supported in any suitable manner other than that shewn, for instance, by suspending it from a ceiling or, by a suitable bracket, from a wall.

20 I claim:

1. A display device for neckties and the like comprising a tie-holding member and a support therefor, the tie-holding member consisting of a block substantially circular

in horizontal cross-section and an apron of 25 rigid material, one edge of which is united to the block but the remainder of which is spaced from and surrounds the block to almost its entire extent, but not completely, so as to leave an opening fitted to receive 30 the knot of a knotted tie.

2. A display device as claimed in claim 1, in which the block defines the frustum of a cone.

3. A display device as claimed in claim 1, 35 in which the block and the apron are integral.

4. A display device as claimed in claim 1, in which the block is provided with a groove 40 communicating with the space between the block and the apron.

5. A display device as claimed in claim 1, 45 in which the block is provided with a groove communicating with the space between the block and the apron and in which a guide pin is inserted within the grooved portion of the block.

LOUIS A. CHAPMAN.
